Patented July 25, 1916.

Inventor,
Harry C. Adam.
By Bakewell & Church Atlys.

UNITED STATES PATENT OFFICE.

HARRY C. ADAM, OF ST. LOUIS, MISSOURI.

DESIGN FOR A LIGHTING-FIXTURE.

49,412.

Specification for Design.

Patented July 25, 1916.

Application filed June 2, 1916. Serial No. 101,414. Term of patent 14 years.

To all whom it may concern:

Be it known that I, HARRY C. ADAM, a citizen of the United States, residing at St. Louis, Missouri, have invented a certain new, original, and ornamental Design for a Lighting-Fixture, of which the following is a specification, reference being had to the accompanying drawing, forming part thereof.

The figure of the drawing is a perspective

view of my new design for a lighting fixture.

I claim:

The design for a lighting fixture, as shown.

HARRY C. ADAM.

Witnesses:

GEORGE R. LADSON,
GEORGE BAKEWELL.
